CLAIM

(22) Filed: **Jan. 8, 2013**

The ornamental design for a device for painting or cleaning behind a toilet tank, as shown and described.

(51) LOC (10) Cl. 23-01

DESCRIPTION

(52) U.S. Cl.

FIG. 1 is a front perspective view of a device for painting or cleaning behind a toilet tank of our invention in use behind a toilet shown in phantom with the phantom arrows showing a possible direction for use, the figure forming no part of this invention;

USPC D32/40; D4/137

FIG. 2 is a top plan view of a device for painting or cleaning behind a toilet tank of our invention based on FIG. 1;

(58) **Field of Classification Search**

FIG. 3 is a bottom plan view of a device for painting or cleaning behind a toilet tank of our invention based on FIG. 2;

USPC D32/40, 46, 48; D4/137; D8/90;
D28/59; 451/526, 539; 15/104.16,
15/210.1, 118, 104.94

FIG. 4 is a side view of a device for painting or cleaning behind a toilet tank of our invention based on FIG. 1;

See application file for complete search history.

FIG. 5 depicts a side view of a device for painting or cleaning behind a toilet tank as a reversed and rotated view of FIG. 4;

(56) **References Cited**

FIG. 6 is an end plan view of a device for painting or cleaning behind a toilet tank of our invention based on FIG. 2; and,

U.S. PATENT DOCUMENTS

FIG. 7 is a rear plan view an end plan view of a device for painting or cleaning behind a toilet tank of our invention as a reversed and rotated view of FIG. 6.
